GARMENT BAGGING DEVICE

William B. Johnson, Knoxville, Tenn.

Application December 29, 1952, Serial No. 328,362

4 Claims. (Cl. 53—241)

This invention relates to a garment bagging device for use in dry cleaning and other establishments where protective bags are placed over garments supported on conventional hangers. The bags used are entirely open at the bottom but closed at the top except for a small, centrally located opening through which the hook of the garment hanger may pass.

It is an object of this invention to provide a garment bagging device having rack means for holding supplies of empty garment bags of different sizes so that such empty bags will be readily accessible to the user of the device.

Another object of this invention is to improve garment bagging devices of the type having a downwardly extending portion with a hook or eye on its end. In this type of device, an empty garment bag is elevated over the downwardly extending portion, a garment hanger with the garment thereon is placed on the hook, and the bag is lowered over the hanger and garment.

A more specific object of this invention is to provide a garment bagging device of the type mentioned above with additional garment hanger support means near the hook or eye but spaced therefrom to support the hanger while the bag is being elevated over the free end of the downwardly extending portion. This construction allows the user to employ both hands in elevating the empty bag while making the provision of brake means to hold the bag in elevated position unnecessary.

It is a further object of this invention to provide a garment bagging device of the type mentioned above which can be used efficiently by two persons at the same time.

All of these objects are accomplished by the garment bagging device of this invention which comprises a pair of spaced upright members supporting therebetween a plurality of bag racks with their bag supporting portions being spaced from each other in stepped relation. Each rack below the uppermost one may have a bag supporting portion on one or both sides of the plane of the upright members. Above one or both of the uprights is a member which projects upwardly and then bends downwardly and has a pair of hooks secured thereto, one of the hooks being located at the free end of the downwardly extending portion and the other hook being located on the upwardly extending portion at about the same level as the other hook.

Other and further objects and advantages will become apparent from the following specification when read in the light of the annexed drawings, in which:

Fig. 1 is a perspective view of my improved garment bagging device;

Fig. 2 is a sectional view diagrammatically indicating the supplies of empty bags and showing a conventional garment hanger on the device; and

Fig. 3 is a perspective view of a modified form of my improved garment bagging device.

Referring now more particularly to Figs. 1 and 2 of the drawings, the numeral 2 designates spaced apart base frame members having a foot portion 3 at each of their

2

ends. The foot portions 3 are provided with shoes or tips 4 of rubber or other suitable material to prevent accidental sliding movement of the device when in use.

Extending upwardly from members 2 are vertical support means or uprights 5 which are held in position by a brace 6 and the bag rack means. Such bag rack means includes first, second and third bag racks 7, 8 and 12, extending between and secured to the uprights.

The first bag supporting rack 7 is horizontal and extends between reducing T's 18 on the tops of uprights 5. The axis of this first rack lies substantially within the plane containing the axes of the two uprights 5. Long, dress size bags 15 are ordinarily folded over this rack.

The second bag supporting rack 8 is below the rack 7 and has two horizontal bag supporting portions 9 and 10. These portions are parallel to the rack 7 and are spaced on opposite sides thereof. Supplies of medium length, suit size bags 16 are folded over each of the bag supporting portions 9 and 10 of this second rack.

The third bag supporting rack 12 is below and similar to the rack 8, the only difference being that the bag supporting portions 13 and 14 are spaced farther apart than the portions 9 and 10 of the rack 8. A supply of short, trouser size bags 17 is folded over each of the portions 13 and 14 of the third rack.

The described rack means has a capacity of approximately five hundred empty bags and offers a number of advantages. The supplies of empty bags are compactly arranged in position for immediate use; a supply of bags of each of the different sizes is readily accessible from either side of the device; and the displacement of the several bag supporting portions in stepped relation permits manipulation of the bags from any one of the supplies without interference from another bag supply or from some structural element of the device.

All of the elements heretofore described, except the tips 4 and the reducing T's 18, may be formed of metal tubing suitably bent and joined as by welding to provide a structure of the illustrated shape. This structure provides a firm base for members 19 which may also be metal tubing if desired. Members 19 are secured to the uprights 5 by the reducing T's 18 and extend upwardly in portions 20 and then downwardly in back-turned portions 21. Garment hanger supporting means 22, here shown as hooks, are provided on the free ends of the portions 21, and garment hanger supporting means 23, also shown here as hooks, are provided on portions 20 at about the level of the hooks 22.

If desired, some or all of the metal parts of this device may be covered with baked enamel of any desired color or colors.

The device is used in the following manner: A hanger 24 with a garment thereon is brought to the device and hung on a hook 23. This leaves both of the hands of the user free for employment in the manipulation of the empty bag. A bag of a size appropriate for protecting the particular garment on the hanger is then removed from one of the supplies of empty bags and elevated over portion 21 so that portion 21 projects into the bag through the small opening in its top. Since the garment is being supported within easy reach on the hook 23, the user may hold the bag in its elevated position with one hand and transfer the garment hanger from the hook 23 to the hook 22 with the other hand. The bag is then lowered over the hanger and garment to complete the bagging operation.

The embodiment of my invention illustrated in Figs. 1 and 2 is suitable for simultaneous use by two persons. This arrangement is obviously more useful than one which could be used by only one person at a time. Because of the presence of my novel bag rack means, this embodiment costs little more than one provided with only one

member 19 and one set of hooks 22 and 23. This embodiment also has the advantage of providing maximum bagging capacity for a given floor area.

The embodiment illustrated in Fig. 3 offers many of the advantages of the embodiment of Figs. 1 and 2 but lacks the bagging capacity thereof. Because it is less expensive, this embodiment may be preferred for installations requiring only small bagging capacity. The structure comprises a pair of uprights 25 corresponding in all respects to the uprights 5. Extending between an elbow 26 on the top of one of the uprights and a reducing T 27 on the top of the other upright is a first bag rack 28 corresponding to the rack 7. Second and third bag racks 29 and 30 are positioned in stepped relation below rack 28 and correspond to racks 8 and 12 except that each of the racks 29 and 30 has only one bag supporting portion instead of two as in Figs. 1 and 2. Extending upwardly from T 27 is a single member 31 corresponding to one of the members 19 and having hooks 32 and 33 thereon corresponding in location and function to hooks 22 and 23 of Figs. 1 and 2.

Having described this invention in detail, it will be understood that the embodiments herein presented are offered only for the purpose of example, and that the invention is to be limited only by the scope of the following claims.

I claim:

1. In a garment bagging device, a base, a member extending upwardly from said base and then downwardly, the downwardly extending portion terminating in a free lower end located close to the upwardly extending portion and being free of any obstruction to the passage of a garment bag thereover, first garment hanger supporting means on the upwardly extending portion of said member at about the same level as the free end of the downwardly extending portion for supporting a garment hanger while a garment bag is being elevated over said free end, and a second garment hanger supporting means on said free end for supporting the garment hanger in position to have the garment bag lowered thereover, the proximity of said first and second garment hanger supporting means being such as to permit the user of the device to transfer a loaded garment hanger from the first to the second garment hanger supporting means without releasing his hold upon a garment bag elevated over said free end.

2. A garment bagging device comprising a pair of spaced uprights, a rack extending between said uprights for supporting a supply of empty garment bags, an elongated member fixed to the upper end of one of said uprights and extending upwardly, then laterally away from the axis of the upright to which it is fixed in a direction opposite to the direction in which said rack extends from that upright, and then downwardly, the downwardly extending portion terminating in a free lower end located close to the upwardly extending portion and being free of any obstruction to the passage of a garment bag thereover, first garment hanger supporting means fixed to the upwardly extending portion of said member on the side thereof facing said downwardly extending portion at about the level of said free end for supporting a loaded garment hanger while an empty garment bag is being elevated over said free end, and second garment hanger supporting means on said free end for supporting the loaded garment hanger in position to have the garment bag lowered thereon, the proximity of said first and sec-

ond garment hanger supporting means being such as to permit the user of the device to transfer a loaded garment hanger from the first to the second garment hanger supporting means without releasing his hold upon a garment bag elevated over said free end.

3. A garment bagging device comprising a pair of spaced uprights, a first bag supporting means extending between said uprights substantially in a plane containing the axes of said uprights, and second bag supporting means extending between said uprights and having a pair of bag supporting portions below and substantially parallel to said first bag supporting means and located on opposite sides of said plane, two spaced members one of which is associated with one of said uprights and the other of which is associated with the other of said uprights, each of said members extending upwardly from the upright with which it is associated, then laterally away from the axis of such upright in a direction opposite to the direction in which said first bag supporting means extends therefrom, and then downwardly, the downwardly extending portion of each member terminating in a free lower end located close to the upwardly extending portion thereof and being free of any obstruction to the passage of a garment bag thereover, first garment hanger supporting means fixed to the upwardly extending portion of each of said members on the side thereof facing the downwardly extending portion at about the level of the free end, and second garment hanger supporting means on each of said free ends, the proximity of the first and second garment hanger supporting means on each of said members being such as to permit a user of the device to transfer a loaded garment hanger from the first to the second garment hanger supporting means without releasing his hold upon a garment bag elevated over the free end of such member.

4. In a garment bagging device, a base, a member extending upwardly from said base and then downwardly, the downwardly extending portion terminating in a free lower end located close to the upwardly extending portion and being free of any obstruction to the passage of a garment bag thereover, a first garment hanger supporting hook on the upwardly extending portion of said member at about the same level as the free end of the downwardly extending portion for supporting a garment hanger while a garment bag is being elevated over said free end, and a second garment hanger supporting hook on said free end for supporting the garment hanger in position to have the garment bag lowered thereover, said first and second hooks having their free ends positioned adjacent each other, the proximity of said first and second garment hanger supporting hooks being such as to permit the user of the device to transfer a loaded garment hanger from the first to the second garment hanger supporting hook without releasing his hold upon a garment bag elevated over said free end of said member.
